OF D 19,005

DESIGN.

H. C. BASCOM.
BOX STOVE.

No. 19,005.

Patented Apr. 9, 1889

UNITED STATES PATENT OFFICE.

HENRY CLAY BASCOM, OF LANSINGBURG, NEW YORK.

DESIGN FOR A BOX-STOVE.

SPECIFICATION forming part of Design No. 19,005, dated April 9, 1889.

Application filed February 28, 1888. Serial No. 265,600. Term of patent 14 years.

To all whom it may concern:

Be it known that I, HENRY CLAY BASCOM, a citizen of the United States, residing in the village of Lansingburg, in the county of 5 Ronsselaer and State of New York, have invented and produced a new and original Design for a Box-Stove, of which the following is a specification, reference being had to the accompanying photographs, forming part 10 thereof.

Figure 1 of the photographs shows an end elevation of my newly-designed box-stove, and Fig. 2 represents a side elevation of the same.

15 The dominant and controlling features of this design are the shapes of the stove-body, its sides and ends, as hereinafter set forth.

As shown in profile in Fig. 1, the sides of the stove-body have their uppermost portions, 20 A, convex, their lower and largest portions, B, also convex, and the intermediate portions, C, concave.

As shown in profile in Fig. 2, the ends of the stove-body have their upper portions, D, 25 convex, their main lower portions, E, also convex, and the intervening portions, F, concave. The ends are also convex in the horizontal direction, and, as shown in Fig. 1, the lateral edges of the ends are convex in their 30 upper parts, g, and throughout the greater lower portions, h, and are concave in the intermediate portions, i, in conformity and coincidence with the aforesaid profile shapes of the sides.

35 As shown by Figs. 1 and 2, the rim J of the top of the stove-body does not overhang the upper portions of the ends and sides, but is conformed to and coincides evenly with the upper edge parts of the convex portions A and D of the sides and ends. The surface 40 ornamentations p and q on the ends and sides of the stove, the shape and ornamentation of its bottom plate, and the shape of the parts K M O of the legs and the ornaments l n r s 45 thereon are not essential or material parts of this design.

Prior to my invention of this design the sides and ends of some box-stoves have had

their main lower portions convex and the remaining upper portions concave in profile 50 view, while the rim of the top of the stove extended laterally outward and overhanging the upper portions of the said sides and ends, an example being shown in my Design patent, No. 14,487, dated December 18, 1883; but I 55 am not aware that prior to my present invention any box-stove had the profiles of its sides and ends convex throughout the upper portions and main lower portions and concave throughout the intermediate portions, or had 60 the rim of the top of the stove-body conformed to and coinciding with the upper convex portions of the sides and ends of the stove, essentially as shown in the accompanying photographs.

65 What I claim is—

1. The design for a box-stove herein shown and described, the same comprising the convex upper portions, A D, convex main lower portions, B E, and intermediate concave portions, C F, of the sides and ends, and the rim J of the top conformed to and coinciding with the said upper convex portions of the ends and sides, as set forth.

2. In a design for a box-stove, the profile 75 shapes of the sides, consisting of the convex upper portions, A, the main lower convex portions, B, and the intermediate concave portions, C, as herein shown and described.

3. In a design for a box-stove, the shapes of 80 the ends, the same having in profile the convex upper portions, D, the main convex lower portions, E, and the intermediate concave portions, F, and being convex in the horizontal direction, and having the lateral edges 85 convex in their upper parts, g, convex throughout the main lower portions, h, and concave in the intermediate portions, i, as herein shown and described.

In testimony whereof I hereunto set my 90 hand, in the presence of two subscribing witnesses, this 24th day of February, 1888.

H. CLAY BASCOM.

Witnesses:

CHARLES H. BENEDICT,
SEYMORE C. HULBERT.
